COMBINED SEPARABLE BUCKLE AND PICTURE CONTAINER

Moses Halio, Rockville Centre, N. Y.

Application June 27, 1950, Serial No. 10,778

Term of patent 7 years

(Cl. D17—1)

To all whom it may concern:

Be it known, that I, Moses Halio a citizen of the United States, residing in Rockville Centre, L. I., in the county of Nassau and State of New York, have invented a new, original, and ornamental Design for a Combined Separable Buckle and Picture Container, of which the following is a specification, reference being had to the accompanying drawing, forming part thereof.

Fig. 1 is a front view of a combined separable buckle and picture container showing my design.

Fig. 2 is the rear view thereof,

Fig. 3 is a perspective view thereof,

Fig. 4 is a front elevational view thereof,

Fig. 5 is the inner view of the upper half of the combined separable buckle and container shown in Figs. 1 and 2, illustrating the hollow portion thereof, and

Fig. 6 is the inner view of the lower half of the combined separable buckle and container, illustrating the hollow portion for the reception of the picture.

I claim:

The ornamental design for a combined separable buckle and picture container, substantially as shown.

MOSES HALIO.
